UNITED STATES PATENT OFFICE.

HARRY E. CARMONY, OF SHELBYVILLE, INDIANA.

MAIL-BOX.

969,038.

Specification of Letters Patent. Patented Aug. 30, 1910.

Application filed June 3, 1910. Serial No. 564,819.

To all whom it may concern:

Be it known that I, HARRY E. CARMONY, a citizen of the United States, and a resident of Shelbyville, in the county of Shelby and State of Indiana, have made certain new and useful Improvements in Mail-Boxes, of which the following is a specification.

My invention is an improvement in mail boxes, and consists in certain novel constructions, and combinations of parts, hereinafter described and claimed.

The object of the invention is to provide a signaling device for mail boxes of the rural free delivery type, wherein the insertion of mail into the box will display a signal automatically.

Referring to the drawings forming a part hereof, Figure 1 is a vertical longitudinal section of the box, Fig. 2 is a section on the line 2—2 of Fig. 1 looking in the direction of the arrows, Fig. 3 is a perspective view looking from below of the false bottom, and Fig. 4 is a similar view of the bracket for supporting the bottom.

In the embodiment of the invention shown, the box consists of a bottom 1, ends 2 and 2^a, and an integral cover plate forming an arched top 3 and sides 4, and connected to the bottom at the side edges thereof, by means of a pocket 5 at each side edge of the plate, which is engaged by a lateral flange 6 on the adjacent edge of the bottom.

The rear end 2^a is provided with an overlying flange 7 at its sides and top, which is received in a pocket 8 at the end of the cover plate, and the front end 2^a is provided at its sides and top with a laterally bent pocket 9, which receives the adjacent end 10 of the cover plate. The bottom edge of the rear end 2^a extends below the bottom at 11, and the bottom edge of the front end 2 is beaded at 12, to receive a rod 13, which is connected at its ends to the sides 4 of the cover plate.

The pocket 9 receives the edge 10 of the cover loosely, and the rod 13 and bead 12 forms a hinge connection, so that the front end may turn down in the manner of a door. The door is normally retained in closed position, by a latch 14, secured to the inner surface of the top 3, and extending through an opening 15 of the door into engagement with a finger-piece 16 riveted to the door at 17.

The latch 14 is resilient, and is provided with a transverse depression which engages

the edge of the opening 15, when the door is closed, to hold it closed, and the latch is released by the finger-piece 16, which is provided with an opening 19, through which the latch passes. When the finger-piece is depressed, the latch is also depressed; thus disengaging the depression from the edge of the opening, and the finger-piece acts also as a means for handling the door.

The false bottom consists of a plate 20, having its side edges flanged upwardly at 21, and the plate fits closely between the side walls of the box, but loose enough to permit it to move freely. At its front end the plate is provided with a central notch 22, and below the notch a flag or signal 23 is supported, on the end of a rod 24, which is provided with an offset portion 25 secured to the bottom of the plate.

The flag or signal is provided with an overlapping flange 26, between which and the body portion the rod passes, and the bottom 1 of the box is slotted at 27 to permit the passage of the flag. Near its rear end a shaft 28 is arranged transversely of the plate, the ends thereof being provided with knife edges 29 and on the opposite side of the shaft from the flag, a yoke 30 extends from the plate, the arms 31 of the yoke being secured to the plate.

The body portion of the yoke is provided with a centrally projecting threaded stem 32, and a weight 33 in the form of a nut having a milled periphery 34 is threaded onto the stem. The weight may be turned toward or from the shaft 28, to properly balance the plate. A bracket is provided for pivotally supporting the plate, the said bracket being formed from a single piece of wire.

The wire is bent to form a transverse bar 35, the ends being bent forwardly at 36 substantially parallel with each other, thence downwardly and upwardly to form bearings 37 for receiving the ends of the shaft, thence laterally at 38 at approximately a right angle to the portions 36, and thence inwardly at 39 to form feet.

The feet 39 and the bar 35 rest on the bottom of the box, and the angle of the portions 38 and 36 with respect to each other may be varied to raise or lower the plate. The weight is of sufficient size to balance the plate, and to hold the false bottom normally in the full line position of Fig. 1. When, however, mail is placed on the plate 20, the weight will be overbalanced, the false bottom

will take the inclined position, shown in dotted lines in Fig. 1, thus pushing the flag 23 through the slot.

If desired the flag may be painted a vivid color, as for instance red, and will effectually call attention to the fact that there is something in the box. The box may be provided with the usual lock if desired. The portion of the bottom cut away to form the slot 27 10 is bent upwardly to form a stop 40 for limiting the downward movement of the plate.

The flag 23 is of sufficient size to attract attention, and is supported somewhat below the plate by the offset of the rod, so that the 15 greater portion thereof will pass through the slot when the plate is depressed.

An arched plate 41 is supported at the front end of the box at the top, beneath the body of the catch 14, and the plate and the 20 catch are held in place by a rod 42, in the form of a staple, the body portion of the rod being outside of the box, and the ends are passed through openings in the box top and in the catch, and clenched as shown at 43 on 25 the inside.

A coil spring 44 is arranged between the ends of the plate, being held in horizontal position, transversely of the box, and the said spring is adapted to hold coins, the 30 coins being inserted between the coils. The coins are thus held safely above the false bottom, and cannot fall out of the box.

The device may be easily applied to existing end opening boxes, merely by forming 35 the slot 27, and inserting the plate 41. The construction is otherwise the same. The bracket for supporting the false bottom is merely laid in place, the false bottom being of suitable length and width to prevent dis- 40 location of the bracket.

It will be evident that the improvement

may be applied to boxes of any kind, since its operation is not dependent upon the form of the box, the device being in fact entirely independent of the box. It is, however, 45 best suited for use with the form of box shown.

I claim:

1. A device of the character specified, comprising a false bottom adapted to be inserted in a mail box, said bottom consisting of a plate, a shaft secured transversely of the plate at one end thereof, a yoke having its arms connected with the shaft, and extending in the opposite direction from the plate, the body of the yoke having projecting therefrom a threaded stem, a weight threaded on the stem, a signal connected with the opposite end of the plate and depending below the same, and a bracket for supporting 60 the plate in the box, said bracket having a substantially triangular support near each end, each of said supports having a bearing in its apex for receiving one end of the shaft on the plate. 65

2. A device of the character specified, comprising a false bottom adapted to be inserted in a mail box, a shaft arranged transversely of the same near one end thereof, a bracket adapted to rest upon the bottom of the box 70 and having a bearing for each end of the shaft, a yoke connected with the shaft and extending in the opposite direction from the bottom, and a counterweight connected with the yoke and adjustable thereon, said bottom having at the opposite end from the shaft a signal depending below the plate. 75

HARRY E. CARMONY.
